UNITED STATES PATENT OFFICE.

HARRY A. KUHN AND WALTER W. MACFARREN, OF PITTSBURGH, PENNSYLVANIA;
SAID MACFARREN ASSIGNOR TO SAID KUHN.

MINING-MACHINE.

1,234,912.

Specification of Letters Patent. Patented July 31, 1917.

Application filed April 13, 1909. Serial No. 488,716.

To all whom it may concern:

Be it known that we, HARRY A. KUHN and WALTER W. MACFARREN, citizens of the United States, residing at Pittsburgh, in the county of Allegheny and State of Pennsylvania, have invented certain new and useful Improvements in Mining-Machines, of which the following is a specification.

Our invention relates to that class of mining machines in which reciprocating picks or punchers are the cutting elements.

The objects of our invention are, to provide a machine which is adapted to mine the entire thickness of a coal seam without the use of explosives; one which is adapted to move forward continuously while cutting a narrow entry or room; to provide a machine which conveys the coal cut by itself to a convenient position for loading the same for transportation out of the mine; and other improvements which will be more fully hereinafter set forth.

The specific object of our invention is to provide a machine adapted to mine coal for coking, for which purpose it is immaterial to what size the coal is reduced by the mining operation, so long as the size of the maximum pieces does not exceed a certain limit. To these ends, our invention comprises the various constructions and arrangements of parts about to be described.

Referring to the drawings, Figure 1 is a plan view of our improved machine, showing the same in working position in a horizontal section through an entry or room. Fig. 2 is a vertical section through the coal seam, showing a side elevation of the machine. Fig. 3 is a diagram illustrating the arrangement of the mechanisms for oscillating the punchers, showing the same in side elevation. Fig. 4 is a vertical section through one of the cuts made by the punchers, showing the relation of the cutting point and the wedging device.

Our machine is entirely different in principle from the ordinary puncher machine, whether provided with a single or multiple pick, the operation of which consists in bringing the pick point successively to all portions of the coal to be cut, so that the same are successively shattered. In our machine, however, only a small portion of the coal is actually cut by the cutting points, it being serrated into lumps, which are then

broken off by a blow delivered at an angle to the direction of cutting.

In this way, much less power is required, as much less coal is actually cut and the coal is generally more uniform in size. A further point of advantage consists in the fact that the mounting of the punchers is such that they need be oscillated in one plane only, thus making the machine more simple and rigid.

The machine consists of a strong frame 1, preferably formed of structural steel. The frame 1 is mounted upon four supporting wheels, the front wheels being designated by the numeral 2, and the rear wheels by the numeral 3.

At the forward end of the machine there is mounted a pair of horizontal disks or saws 4, for undercutting. Adjacent to the saws 4 there is placed a pair of conveyors 5, for removing the coal. Secured to the forward end of the frame 1, and above the saws 4, there are three series of horizontally oscillating pneumatic punchers, the lower series being designated by the numeral 6, the middle series by the numeral 7, and the lower series by the numeral 8. The individual punchers in each series are designated by sub-scripts "a," "b," and "c", reading from the left side of the machine toward the right side. The lower series of punchers, 6_a, 6_b, and 6_c are each pivoted about a vertical pivot, so as to swing in a horizontal plane.

The outer punchers 6_a and 6_c are pivoted by the pins 9 to the overhanging brackets 10. The center puncher 6_b is pivoted by the pin 11 to the bracket 12. The brackets 10 and 12 are secured to the frame 1.

The punchers 7_a, 7_b, 7_c, 8_a, 8_b, and 8_c are similarly mounted. Each puncher cylinder has secured to its rear end a bracket or lug, 13. The brackets 13 of each horizontal series of punchers are connected by the links 14, so as to oscillate together. Power for the oscillation of the upper two series of punchers is supplied by an eccentric 15, operating a rod 16, which is connected by the pin 17 to an end of the levers 18. The levers 18 are pivoted by the fixed pins 19 to the frame 1.

Pins 20 connect levers 18 with links 21, which in turn are connected to the bracket 13 upon one of the punchers. The eccentric

15 operates the two upper series of punchers, and a second eccentric 22 is provided to similarly operate the lower series of punchers.

The eccentric 15 is mounted upon a shaft 28, which may be supported in suitable bearings secured to the frame 1. The shaft 23 forms the crank shaft of a small two-cylinder compressed air motor 25, which latter is secured to the frame 1.

10 A sprocket 26 is mounted upon the shaft 23, adjacent to the motor 25, and drives, by means of a chain 27, a similar sprocket upon the shaft 28. The shaft 23 carries the eccentric 22.

15 The compressed air motor 25 is of the two-cylinder double-acting type, with cranks at 90°, and may be run at a variable speed in either direction, so that by means of a throttle valve and reversing lever, the operator 20 may have full control over the oscillation of the three series of punchers.

A compressed air motor 29 of similar type is provided to drive the saws 4 and the conveyers 5 as follows:—The motor 29 has a 25 crank shaft 30 extended at both ends into the bearings 31 secured to the frame 1. Mounted upon the shaft 30 at each side of the motor 29, there is a worm 32, these worms being of the opposite hand as shown. The 30 worms 32 mesh with and drive worm gears 33 upon the vertical shafts 34, these latter being supported in suitable bearings secured to the frame 1.

Sprockets 35 are also mounted upon the 35 shafts 34, which sprockets drive chains 36, each of which engages and drives a sprocket 37 upon the vertical saw shafts 38, which latter are supported in bearings 39 extended from the front end of the frame 1.

40 At the extreme lower ends of shafts 34, conveyer sprockets 40 are provided to drive the conveyer chains 41. A pair of idler sprockets 42 is provided at the rear of the machine for the conveyers 5.

45 The conveyer chains 41 are provided with flights 43, which carry the coal from the front of the machine and deliver the same to a chute 44, from which it may be handled either directly into cars, or by other mechanism.

The coal broken down by the punchers falls upon the saws 4, from which it is thrown off upon the conveyer plate 45. Flights 43 of the conveyers 5 slide on the 55 plate 45 and scrape the coal toward the rear of the machine.

Power may be supplied to drive all the motions of the machine from an electric motor 46, or compressed air may be led into 60 the mine from an outside power plant and the machine driven directly by the air without the use of electricity.

The armature shaft 47 of the motor 46 has mounted thereon a sprocket 48 driving 65 chain 49, which in turn drives a sprocket 50,

mounted upon the crank shaft 51 of the air compressor 52. The air compressor 52 is shown as being of the four-cylinder vertical type, although any other style of compressor may be used.

70 Reservoirs 53 are provided for the reception of the air from the compressor 52, from which it may be lead to the various motors and punchers. The pipe connections and valves for this purpose being well understood, they have not been illustrated, as tending merely to confuse the drawings.

75 The rear truck wheels 3 are mounted upon an axle 54 extending clear across the machine and supported in the bearings 55 secured to the frame 1. At the center of the axle 54 is mounted the gear 56. The gear 56 is driven by a gear 57 mounted upon the crank shaft of the two-cylinder air motor 58, this latter being secured to the frame 1.

80 The motor 58 is of the double-acting reversing type, and may be run at any desired speed and in either direction. Power is applied by the motor 58 through the gears 56 and 57 to the axle 54, and thence to the wheels 3, which are secured to the axle 54. The axle 54 is extended through the wheels 3 to carry the sprockets 59. The sprockets 59 actuate the chains 60, which in turn drive the sprockets 61, which latter are secured to the front truck wheels 2. By this connection with the rear axle 54, the front wheels 2 are simultaneously driven.

85 The conveyer plate 45 is secured at its forward end to the frame 1, and supported at its rear end by a pair of carrying wheels 62, mounted upon an axle 63, which is carried by the bracket 64 secured to the plate 45. The conveyer plate 45 extends horizontally from the front of the machine back to a point forward of the rear truck wheels 3, from which point it makes a vertical curve as shown in Fig. 2, in order to secure a sufficient elevation of the coal for the same to be discharged by gravity from the chute 44.

90 The punchers 6, 7, and 8 are all duplicates and of ordinary construction such as are used for coal mining and stone channeling.

95 The piston rods 65 are provided with a tapered or shouldered forward end adapted to receive a U-shaped cutting yoke 66, which may be secured to the piston rod 65 by nut 67. The cutting yoke 66 is provided with a pair of chisel-shaped cutting points 68 at its forward extremity. Near the rear of the yoke 66, there is formed a pair of wedge-shaped projections 69.

100 In Fig. 4, we have illustrated this construction on an enlarged scale. As the chisel points 68 are advanced into the coal, 105 they cut a pair of slots 70. After these slots 70 have reached a certain depth, a wedge-shaped projection 69 will strike the rear end of the lump 71 between the slots 70, and the jarring action caused by said blow will be 110

sufficient to break off the lump and sever it from the native coal bed, after which it will fall on the saws 4 and be discharged from them to the conveyer plate 45.

5. The stroke of the punchers will be considerably less than the depth of the slots 70, so that when the lump 71 is severed from the native coal by the wedge-shaped projections 69, it may lie for an instant on the 10 lower fork of the yoke 66. However, as the punchers are being continuously oscillated, in a short time they will have moved sideways a sufficient distance to release the severed lumps, which may then fall as before 15 described.

The peculiar arrangement of the three series of punchers is shown plainly in Fig. 2. The machine, as a whole, acts to cut a series of slots in the coal, the lower ones in advance 20 of the upper ones, so that a breaking point is provided for each lump.

The saws 4 are first advanced under the whole body of coal; punchers 6 then operate to cut a pair of slots above the slot cut by 25 the saws 4 and to the rear of the forward extremity of the saws 4; the punchers 7 then operate to cut a second pair of slots above the slots cut by the punchers 6 and to the rear thereof; and in a similar manner the 30 punchers 8 are adapted to cut a third series of slots above the slots made by punchers 7 and to the rear thereof.

It will thus be seen that as the wedge shaped projections on any of the cutting 35 yokes 66 strike a projecting lump, clearance will have been provided for that lump to break and fall from its original position.

It will be observed that, by connecting each series of punchers by the links 14, the 40 cutting points in each series are always simultaneously swung in the same direction, so that there can be no interference between them. However, for the better balancing of the machine, one series of punchers is swung 45 in a direction contrary to that of the other two series.

From the above description, the operation of our improved machine will be readily understood. The machine is brought to the 50 desired place of working and connected with the source of power, as, in the present instance, to an electric wire.

The motor 46 is then started to operate the air compressor 52. Compressed air is 55 then supplied to all the punchers, and a common throttle valve may be used for this purpose. The motor 25 is then started to automatically oscillate the punchers; the motor 29 is started to operate the saws and 60 conveyers; and, lastly, the motor 58 is started to give a slow forward feed to the whole mechanism after the several parts as above described are in operation, and the machine may be continuously advanced into the coal.

65 It will be noted that as the motor 58 is

of the two-cylinder reversing type, with cranks at 90° similar to the driving gear of a locomotive, it will propel the machine at practically any speed, so long as the size of the cylinders and the air pressure together will produce a torque sufficient to propel the machine.

70 It will also be noted that as the air supplied to motor 58 is an elastic fluid, this means of propulsion produces an elastic feed 75 of the machine into the coal. The resistance offered by the weight of the machine and the friction of the truck wheels will be practically constant, and the resistance offered by the undercutting saws will be in 80 proportion to the hardness of the material being cut.

The punchers will offer practically no resistance to the advance of the machine as long as they are working freely, so that by 85 properly proportioning the size of the motor 58 to the work of advancing the machine against its resistance to traction and the resistance offered by the saws 4, or by the use of a graduated reducing valve between reservoirs 53 and motor 58, by which the required pressure on motor 58 may be experimentally determined, it will be possible to advance the machine elastically in proportion to the 90 resistance encountered.

95 The same elastic action will be produced by the motor 29 with reference to the saws and conveyers, so that should material of unusual hardness be cut by the saws, or an unusual load carried by the conveyer, the 100 motor 29 will automatically slow down to relieve the strains caused by these excess loads.

The above features are very important from an operating standpoint, as being conducive to long life of the parts affected.

Owing to the fact that the air required by the punchers and motors is compressed almost immediately before use, the reservoirs 53 being merely provided to absorb the 110 fluctuations of the several mechanisms, it will be apparent that the efficiency of the compressed air system will be much higher by reason of the air being used hot, thus utilizing the heat of compression, than if the 115 air were compressed in a stationary power plant outside the mine and led therein through a long line of pipe, in which it would cool to mine temperature.

Many variations in design and construction may be made by those skilled in the arts of building and operating such machines without departing from the spirit of our invention, and we therefore desire to claim and hold as ours all patentable subject matter 125 covered by the following claims:

1. In a mining machine, a frame, an undercutting device mounted thereon, and a plurality of reciprocating punchers mounted above said undercutting device in differ- 130

- ent horizontal planes, each of said punchers being mounted on an individual vertical pivot rigidly secured to said frame, and means for simultaneously oscillating the 5 punchers at different levels in opposite directions.
2. In a mining machine, a frame, a pair of undercutting saws mounted thereon in a horizontal plane, and running in opposite 10 directions, and a plurality of reciprocating punchers arranged above each of said saws in different horizontal planes, each puncher having an individual vertical pivot secured to said frame.
- 15 3. In a mining machine, a frame, a pair of undercutting saws mounted thereon in a horizontal plane and running in opposite directions, and a plurality of series of horizontally swinging punchers in different 20 horizontal planes above said saws.
4. In a mining machine, a series of pivoted punchers at one level and a second series of pivoted punchers at a higher level and behind the first.
- 25 5. In a mining machine, a series of pivoted punchers at one level, a second series of pivoted punchers at a higher level, and behind the first series, a third series of pivoted punchers at a still higher level and behind 30 the second series.
6. In a mining machine, a frame, an undercutting device mounted thereon, and three individually pivoted punchers mounted above said undercutting device and vertically *en échelon*.
- 35 7. In a mining machine, two series of horizontally swinging reciprocating punchers mounted one above the other, a motor, a connection from said motor to swing the upper 40 series of punchers in one direction and a connection from the motor to swing the lower series in opposed relation to the upper series.
- 45 8. In a mining machine, a frame, an undercutting device mounted thereon, a series of horizontally swinging reciprocating punchers above said undercutting device and connected each to another for simultaneous oscillation, a second series of horizontally swinging punchers above said first 50 series, said second series being also connected for simultaneous horizontal oscillation, a motor, and mechanism connecting said motor and all of said punchers to swing the 55 latter in simultaneous parallel relation.
9. In a mining machine, an oscillating
- puncher adapted to cut a groove and a dislodging device on the moving member of said puncher adapted to dislodge the coal at the side of said groove, when said groove 60 has reached a certain depth.
10. In a mining machine, an oscillating puncher adapted to cut a groove, and a wedge carried by the moving member of said puncher adapted to dislodge the coal 65 at the side of said groove, when said groove has reached a certain depth.
11. In a mining machine, a series of oscillating punchers adapted to cut a common groove and a dislodging device carried by 70 each of the moving elements of said punchers to impinge upon the coal at the side of said groove when said groove has reached a certain depth.
12. In a mining machine, a frame, a plurality of reciprocating punchers thereon arranged to cut horizontal slots in the coal, a pair of undercutting saws below said punchers, having their adjacent edges rotating toward said frame, and a pair of conveyors 75 80 having cantaliver flights, adjacent flights in the two conveyors moving in the same direction as the adjacent edges of said undercutting saws.
13. In a mining machine, a frame, a unit 85 reciprocating member adapted to make a crevice like opening in the coal, said member carrying a projecting surface arranged to force the coal adjacent to the opening to one side as the unit member advances, said projecting surface having a sharp shoulder 90 adapted to catch and draw the coal on the backward stroke of said member when said member has advanced in the coal a certain distance.
14. In a mining machine, a frame, a reciprocating member supported on said frame, means carried by said reciprocating member to make a kerf-like opening in the coal, a wedge-shaped projection carried by said reciprocating member to press on the coal at 95 the side of the opening as said member advances, a sharp shoulder on said projection adapted to engage the coal on the backward stroke of said member, means to move the 100 member sidewise.
